UNITED STATES PATENT OFFICE.

ABRAM C. MOTT, OF PHILADELPHIA, PENNSYLVANIA.

DESIGN FOR A WATER-FRONT FOR HEATING-FURNACES.

SPECIFICATION forming part of Design No. 26,998, dated April 27, 1897.

Application filed March 20, 1897. Serial No. 628,543. Term of patent 14 years.

To all whom it may concern:

Be it known that I, ABRAM C. MOTT, a citizen of the United States, residing in Philadelphia, Pennsylvania, have invented a certain new and useful Design for a Water-Front for Heating-Furnaces, of which the following is a specification.

My design for the water-front of a house-heating furnace is fully illustrated in the accompanying drawings, in which—

Figure 1 is a view of the water-front in perspective; and Fig. 2 is a sectional view on the line 2 2, Fig. 1.

The essential feature of the design is the quadrangular casing with a central opening.

A is the quadrangular hollow frame, having a quadrangular central opening a. a' are

projections extending from the under side of the hollow frame, and at one end are perforated bosses b b, and at the top are a series of 20 lugs c c. On the face of the frame are perforated lugs d d.

I claim—

The design for the water-front of a heating-furnace, as herein described and as shown in 25 the accompanying drawings.

In testimony whereof I have signed my name to this specification in the presence of two subscribing witnesses.

ABRAM C. MOTT.
